GAS TUBE REFLECTIVE SURFACE IONIZABLE BY HIGH ENERGY ELECTROMAGNETIC WAVES

Thomas E. Manwarren, Fernwood, N.Y., assignor to General Electric Company, a corporation of New York

Filed Feb. 27, 1963, Ser. No. 261,444

14 Claims. (Cl. 333—13)

This invention relates to the transmission and reception of microwaves and in particular it relates to microwave switches or duplexers permitting the alternate transmission of high power signals and the reception of weak signals through a single antenna system.

Known prior art devices include combinations of special TR tubes (or transmit-receive tubes) with resonant cavities in which the TR tubes are placed at or near the center of the cavities. These prior art devices have the desirable effect of reducing the RF, or radio frequency, current in the glow discharge by a factor related to the input coupling susceptance to the cavity, but present disadvantages which are explained below. A variation of these known prior art devices involves the use of a reactance in series with the glow discharge of a TR tube. This latter configuration serves to reduce the RF current in the discharge by a factor related to the value of the reactance used. Both known configurations of these prior art devices are placed in a resonant cavity and consequently they both have the disadvantage of reducing the instantaneous bandwidth of the signal which can be transmitted to a value proportional to f_0/Q_1 , where f_0 is the central frequency and Q_1 is the loaded Q of the cavity. In addition to reducing the bandwidth, both of these systems increase the insertion loss for low level signals. Another limitation of the prior art devices is that they are functional only as lumped or distributed parameters which means they must be of small size relative to the wavelengths of the energy being handled and may not be employed to form images with, or to collimate, the energy received.

It is therefore an object of this invention to provide a transmit-receive device capable of handling high power RF signals without a reduction in bandwidth.

It is an additional object of this invention to provide an improved transmit-receive system which is not limited in bandwidth by resonant devices.

It is a further object of this invention to provide a duplexer capable of operating with only a single TR tube, or else with a number of TR tubes placed together to function as a unit.

It is another object of this invention to provide a duplexer having the ability to control large amounts of energy and at the same time to transmit a wide bandwidth limited only by the capacity of the waveguides used to feed the device.

It is still another object of this invention to provide improved bandwidth and power handling capabilities in a radar transmit-receive element with small insertion losses.

It is yet another object of this invention to reduce the current density of the RF current in the glow discharge of a transmit-receive device.

It is still a further object of this invention to provide means for transmitting low level and for reflecting high level electromagnetic energy such that a controlled plane or curved constant phase contour is formed in the reflected high energy wave,

It is yet a further object of this invention to provide means for transmitting low level and for reflecting high level electromagnetic energy so that, depending on the curvature of the reflecting-transmitting means, real or virtual images may be formed from the reflected and/or the transmitted energy, and

2

It is yet another object of this invention to provide improved means for collimating high power electromagnetic signals.

The novel features that I consider characteristic of my invention are set forth with particularity in the appended claims. The invention itself, however, both as to its organization and its method of operation, together with additional objects and advantages thereof, will best be understood from the following description of specific embodiments when read in connection with the accompanying drawings, in which:

FIG. 1 is a sectional view of an embodiment of this invention,

FIG. 2 is a view of another embodiment of the invention showing some details in perspective,

FIG. 3 is a block diagram of a duplexer which incorporates elements like those shown in FIG. 1 and in FIG. 2,

FIG. 4 is a sectional plan view of an embodiment of the invention of use as a complete duplexer,

FIG. 5 is a sectional view of an embodiment of the invention also of use as a complete duplexer, and

FIG. 5a is perspective view of a TR device suitable for use in the duplexer of FIG. 5,

FIG. 6 is a sectional view of yet another embodiment of the invention of use as a complete duplexer.

FIG. 6a is a perspective view of an alternative form of TR device suitable for use in the duplexer of FIG. 6.

Briefly, the invention involves the receipt of RF signals into a volume of ionizable gas having a relatively large dimension perpendicular to the direction of propagation of the RF signals and shallow depth in the direction of propagation of the RF signals. In a preferred embodiment of the invention, this configuration of the gas volume is provided by expanding the area of a vessel containing the gas in a way to enlarge its cross sectional area to impinge RF signals. If the RF signals are of low energy level they will pass through the gas with little or no effect, but if the RF signals are of high energy level they will ionize the gas and subsequent high energy signals

will be reflected by the ionized gas. Reflections from the ionized gas will be able to form virtual images when the ionized gas is held in containers so that it presents either a flat configuration or one having a convex curve on the signal receiving side. The reflections will be able to form real images if they come from a concave curve on the side on which the high energy RF signals are received. The reflections will be directed back along the path traveled by the RF signals if the ionized gas is held in flat or tubular vessels.

Turning to FIG. 1, we find an embodiment of the present invention located between a waveguide input at 2 and a waveguide output at 4. Waveguide sections are shown as sectional views of FIG. 1 at 6 and 8 with sections expanded in either the E plane or the H plane, or both, as indicated at 10 and 12. The expanded waveguide sections are connected through a transmit-receive tube, or TR tube, which is labeled TR-2. In the configuration shown in FIG. 1, high energy microwaves supplied to the waveguide input at 2 and through waveguides at 6 and 10 will impinge on the TR tube TR-2 and gas contained in the tube will be highly ionized so that most of the energy will be reflected back through the waveguide sections 10 and 6 to the waveguide input at 2 for transmission through a suitably coupled antenna. In receive periods, low energy signals received by the antenna can be accepted through the waveguide input at 2, through the waveguide sections 6 and 10 and through the TR tube TR-2. These low energy signals will produce no ionization in the tube due to their low energy level so that received signals can pass through the TR tube and the

waveguide sections 12, 8 and 4 to be supplied as usable signals.

The function of the TR tube TR-2 is to serve as a kind of gate or switch which will close if the surge of energy received is too great, but will remain open if the energy level received is low. Tubes of the type depicted at TR-2 are shown in the copending application of Thomas E. Manwarren and Robert J. Jones, Serial Number 225,939, filed on September 24, 1962, now Patent No. 3,209,285 and assigned to the U.S. Government. These tubes consist of concentric glass walls which are closely spaced throughout their greater length, somewhat as the tubes used in embodiments of the present invention as indicated by the bracket 11 in FIG. 1, but have a relatively large opening, such as is indicated by bracket 13, between them at one end. The small space between the glass walls in the longer portion of the tube serves as a shallow space in which an easily ionized gas such as argon may be confined for ready ionization. The larger open space at one end of the tube serves as a reservoir for additional gas molecules as the gas is gradually dissipated into the glass walls of the tube. In the configuration of the invention shown in FIG. 1, the total energy incident on the TR-2 tube would be about the same as would impinge on the tube if the tube were placed in the input waveguide 2. However, by the use of the configuration shown in FIG. 1 with an expanded area along the sides of the tube TR-2, the current density at any point in the glow discharge is reduced. The amount of the reduction in the current density is a factor roughly proportional to the area of the tube exposed to the input signal.

The invention as shown in FIG. 1 within the dashed line 9 may be called a TR unit for convenience and has been so labeled. The use of this term "TR unit" will be helpful in describing the application of the invention as shown in FIG. 1 to a complete duplexer circuit, such as that illustrated in FIG. 3. In FIG. 3 the transmitter T-2 supplies a high power microwave signal to a conventional hybrid device or hybrid waveguide junction, H-2, such as is conventionally used in microwave circuits. In such hybrids a received signal from a source such as T₂ may be split to be transmitted to TR units such as those indicated at D-2 and D-4. With high energy microwaves being transmitted from the hybrid to the TR units D-2 and D-4, a state of ionization will be provided in the TR tubes contained in the TR units. This ionization will provide virtually total reflection of the microwave signals back to the hybrid and from there to the antenna for transmission. Reflected microwave signals from suitable targets which are received at the antenna A-2, on the other hand, will be relatively weak and will be transmitted through the hybrid H-2 to the duplexers D-2 and D-4 where they will produce no ionization of the gas in the TR tubes and will be transmitted to the hybrid H-4 and the receiver R-2. The load indicated by the block L-2, it will be recognized, is primarily a means of disposing of any high energy microwave signals which may leak through the TR units D-2 and D-4.

A device such as the TR unit of FIG. 1 will function satisfactorily in conjunction with a complete circuit such as that shown in FIG. 3, providing the aperture of the waveguide and of the tube TR-2 is not too large relative to the waveguide members 6 and 8. If the aperture is made too large, that is if the large dimension along the tube TR-2 is too great, phase errors may be generated which will distort the uniform phase front which is desired for energy reflected by the TR tube or transmitted by it. If phase errors are generated, there will be reflection losses for low level energy passing from one side of the tube to the other. One way to remedy this situation is to shape the TR-2 tube so that when the ionized gases function as a mirror reflecting high energy signals, the mirror is shaped to reflect each part of the wave back along the path through which it came. The shape of the tube can

at the same time be made so that it functions like a lens to transmit low energy signals without aberration.

Another embodiment of the invention, which avoids these problems and allows further reductions in current density, is shown in FIG. 2. In the devices shown in FIG. 2, energy from a feedhorn at 20 is reflected from a surface having a parabolic curve or a parabola at 22 to form a plane constant phase contour incident on the TR tube TR-20. Low level energy from waveguide input 20 passes through the tube TR-20, is reflected by a second parabola at 24, and focused on the feedhorn 26 with very little loss. High level energy on the other hand ionizes the gas in tube TR-20 which then acts as a reflector to reflect the energy back to parabola 22. The parabola 22 then reflects the energy to the feedhorn 20 which transmits the energy through the waveguide input for further use. This complete device acts as a bandpass transmitt-receive device and two of them can be used in a balanced duplexer when connected as shown in FIG. 3 in place of D-2 and D-4.

The embodiment of the invention shown in FIG. 2 can of course be expanded in three dimensions so that the parabolas at 22 and 24 become paraboloids. However, it is expected that E or H plane pillboxes should suffice to handle transmitted power levels higher than can now be generated, consequently expansion of the parabolas to three dimensions is presently unnecessary. It is of interest to note that the E plane TE₀₁ pillbox offers a distinct advantage over the H plane type in that all RF current in the tube flows parallel to the tube axis and there is no RF current flowing into the flow discharge from the pillbox metal walls except at the ends. At the ends, the current density in the tube can be made small by designing the feedhorn to illuminate the parabola or parabolic contour at a low power level. A folded or double layer pillbox of conventional design may be used to avoid a voltage standing wave ratio or VSWR being generated at the horns by energy reflected back to the horn from the central portion of the parabola. In each a folded pillbox, a feedhorn such as 20 in FIG. 2 would be in a separate chamber of the pillbox parallel to the chamber shown in FIG. 2. High level energy from the feedhorn would be transmitted through a passage connecting the two chambers along the curve 22 to ionize the gas in tube TR-20 and be reflected back.

An additional embodiment of the invention is shown in a sectional view in FIG. 4 where a circular pillbox at 40 has four horns spaced 90° apart and arranged to face the inner wall of the circular pillbox. The four horns have been labeled T-40, for transmitter horn, A-40 for antenna horn, L-40 for load horn and R-40 for receiver horn. These horns are shown with suitable ports at P-40, P-41, P-42 and P-43 respectively through which microwave signals may be transmitted. In this configuration only one TR tube, shown as TR-40, is required to completed the duplexer function. The TR tube in this instance may be of cylindrical cross section, rather than being flat sided or of other curved shape, since most of the reflections in a flat walled pillbox of this kind will be properly oriented if reflected by ions held in a cylindrical tube. In the operation of the embodiment of the invention shown in FIG. 4, high level energy received through the port P-40 of the transmitter input horn indicated at T-40 is reflected off the inner side of the circular wall of the pillbox 40. The circular contour of the pillbox 40 functions satisfactorily as a collimating device providing a proper choice is made of the F/D ratio where F is the focal length of the horn and D is the length of a chord along the arc illuminated on the inside of the circular pillbox. In this connection, it will be recognized that with the proper ratio of F to D the circular contour approximates a parabola. The highly collimated signal reflected off the inner face of the circular pillbox is a plane wave which will be incident on the TR tube TR-40 at an angle of 45° with respect to the tube axis. This

high power signal ionizes the gas within the tube, as previously explained, and is reflected in the form of a plane wave to impinge upon the circular wall facing the antenna horn A-40. The signal is reflected by a section of the cylindrical wall of the pillbox and focused at the antenna output arm horn A-40 for transmission through the port P-41 to the antenna, which is not shown. Any high power microwaves which leak past the tube TR-40 will be focused by the interior of the circular pillbox into the load output horn L-40 and will be dissipated by a load circuit connected to the output port P-42 in the manner described with respect to FIG. 3.

During receive periods, the duplexer shown in FIG. 4 will receive low level energy from the antenna arm through a port P-41 and through the horn A-40. This low level energy will be reflected from the interior wall of the pillbox opposite the horn A-40 and transmitted as a collimated signal through the un-ionized tube TR-40 to be reflected by the opposite wall of the pillbox and focused at the receiver arm R-40 for transmission through the port P-43 to the receiver. The curved walls of the pillbox may be cylindrical walls, or parabolic walls, or may be folded into a double layer with the feedhorn in a separate layer in order to avoid reflections caused by the presence of the feedhorn blocking the apertures. It will be recognized that the embodiment of the invention illustrated in FIG. 4 need not be confined to a shallow pillbox, but that it may be expanded in two planes as much as desired in order to increase the power handling ability of the system. The tube TR-40 may be cylindrical in shape with its greatest dimension along its axis, as indicated.

An additional configuration of the invention in which the duplexer actually becomes a part of the antenna feed is illustrated in FIG. 5. In the operation of the apparatus shown in FIG. 5 high intensity energy radiated from a transmitter horn at T-50 will ionize the gase in TR tubes at TR-50 and be reflected from the plane reflector formed by the TR tubes to the face of a parabola or paraboloid at 50 to form a virtual image of the transmitter horn at the parabola or paraboloid focal point. The receive horn R-50 is isolated from the transmitter horn during transmit periods because of the TR tubes which may be a number of tubes placed side by side, as FIG. 5a illustrates by way of example, or a large flat tube or tubes. During a receive period energy collected by the paraboloid will pass through the un-ionized TR tubes and be focused at the focal point of the paraboloid which is also the receiving point of the receive horn R-50.

The TR tubes of FIG. 5 may be shaped in a particular manner by bending or by flattening and then bending to vary the effective focal length during the transmit period as in a Cassegrainian telescope system such as is illustrated in FIG. 6. FIG. 6 shows a transmitter horn at T-60 located approximately at the vertex of a paraboloid antenna 60 with a small aperture in the center of the paraboloid through which high powered signals may be passed. The transmitted signals strike one part of a hyperboloid shaped configuration at 62 which is composed either of a single large TR tube (see FIG. 6a) or a number of small TR tubes designated at TR-62 such that gas in the tubes becomes ionized and reflects the high energy signals into the face of the paraboloid at 60. The paraboloid 60 then transmits the signals in the desired collimated fashion. During the receive time, the paraboloid 60 will reflect received signals through the hyperboloid 62 to the receive horn R-60 for use as previously described.

The relative dimensions of the TR tubes employed in embodiments of this invention are of such significance to the invention that further comments are in order. It has been noted that most, if not all, of the prior art TR tubes have been limited in size to cross sectional areas which are small enough so that their operating parts

could be contained within the walls of waveguides. The cross sectional dimensions of waveguides are generally smaller than a wavelength, consequently the prior art TR tubes have also been constrained to be smaller in their maximum usable dimensions than a wavelength. With such small dimensions, the prior art TR tubes have functioned only as lumped or distributed parameters which concentrated energy in a small volume and have been incapable of forming images. With the much larger dimensions of embodiments of the present invention, new relationships are brought into play and the TR tubes may be categorized as collimating and/or focusing devices. Such collimating and focusing devices can distribute energy over a much larger area than can lumped parameters so that high energy levels are less likely to be damaging. In addition to providing more effective means for controlling the transmission of large amounts of energy, the introduction of relatively large TR elements makes it possible to focus both high and low level energy to form either real or virtual images, depending on the curvature of the TR elements.

While the principles of the invention have now been made clear, there will be immediately obvious to those skilled in the art many modifications in structure, arrangement, proportions, the elements and components used in the practice of the invention, and otherwise, which are particularly adapted for specific environments and operating requirements without departing from those principles. The appended claims are therefore intended to cover and embrace any such modifications within the limits of the true spirit and scope of the invention.

What I claim as new and desire to secure by Letters Patent of the United States is:

1. A reflector for high energy microwave comprising a closed container having walls spaced in close proximity relative to the length of the container, an ionizable gas contained in the space between said walls, said closed container having a shape corresponding to that of a desired reflector, said closed container and said ionizable gas being transparent to low energy microwaves, and said closed container operating as a reflector capable of forming real images from said high energy microwaves when said ionizable gas becomes dissociated into its ions under bombardment by said high energy microwaves.

2. A reflector for high level electromagnetic energy comprising a closed container having walls spaced together in close proximity relative to the wavelength of said high level electromagnetic energy, an ionizable gas contained in the space between said walls, said walls having a shape corresponding to that of a desired reflector, said closed container having a dimension in at least one direction of a magnitude at least equal to the wavelength of said high level electromagnetic energy, said closed container and said ionizable gas being transparent to low level electromagnetic energy and said ionizable gas functioning as a reflector capable of forming an image from said high level electromagnetic energy when said ionizable gas becomes dissociated into its ions under bombardment by said high level electromagnetic energy.

3. A reflector for high level electromagnetic energy comprising a closed container having walls spaced together in close proximity relative to the wavelength of said high level electromagnetic energy, an ionizable gas contained in the space between said walls, said walls having a shape corresponding to that of a desired reflector, said closed container having a dimension in at least one direction of a magnitude sufficient to enable the formation of an image from said high level electromagnetic energy, said closed container and said ionizable gas being transparent to low level electromagnetic energy and said ionizable gas functioning as a reflector having said desired shape when said ionizable gas becomes dissociated into its ions under bombardment by said high level electromagnetic energy.

4. In a duplexer for transmitting low energy microwaves and for reflecting high energy microwaves, means including a closed container having a configuration such that it may be placed to fill a pathway of said microwaves, said closed container incorporating a thin volume of ionizable gas within contoured walls, said closed container and ionizable gas being transparent to low energy microwaves, but said ionizable gas becoming dissociated into its ions in the presence of high energy microwaves to form a reflector shaped by said contoured walls, said reflector serving to form images of said high energy microwaves along lines perpendicular to the direction of propagation of said high energy microwaves.

5. In a duplexer for transmitting low energy microwaves and for reflecting high energy microwaves, means including a passageway for transmitting said microwaves, a closed container having a configuration to effectively fill said passageway, said closed container incorporating a thin volume of ionizable gas within contoured walls, said closed container and ionizable gas remaining transparent to low energy microwaves, but said ionizable gas becoming dissociated into its ions in the presence of high energy microwaves to form a reflector shaped by said contoured walls, said reflector serving to form images of said high energy microwaves in planes perpendicular to the direction of propagation of said high energy waves.

6. In a microwave control device for transmitting low energy microwaves and for reflecting high energy microwaves, means including a passageway for transmitting said microwaves, means including an expanded section of said passageway expanded in at least one plane to a size substantially equal to the magnitude of a wavelength of said high energy microwaves, means for effectively filling said expanded section of passageway including a closed container, said closed container incorporating a thin volume of ionizable gas, said closed container and ionizable gas remaining transparent to low energy microwaves, but said ionizable gas becoming dissociated into its ions in the presence of high energy microwaves to form a reflector for said high energy waves said reflector serving to form images of said high energy microwaves along lines perpendicular to the direction of propagation of said high energy waves.

7. A wave controlling device comprising plural layers of material sealed to form closed spaces, an ionizable gas filling said spaces, said layers of material having radii of curvature of selected magnitude to form surfaces of a shape such that suitable coatings would cause them to reflect energy to form images, said surfaces and enclosed gas being transparent to low energy microwaves, said enclosed gas becoming ionized in the presence of high energy microwaves to form a reflecting zone shaped by said surfaces said reflecting zone being of shape such that the images formed by reflection therefrom are along lines perpendicular to the direction of propagation of the reflected wave.

8. A device for separating low energy electromagnetic waves from high energy electromagnetic waves and for focusing said separated high energy electromagnetic waves comprising a container having closely spaced walls of selected curvature, said container enclosing a quantity of ionizable gas, said walls and ionizable gas being transparent to low energy electromagnetic waves, said ionizable gas becoming dissociated into its ions when subjected to high energy electromagnetic waves and acting as a reflector, said selected curvature of said closely spaced walls determining the shape of said reflector and the plate at which said high energy waves may be focused.

9. A device for separating low energy electromagnetic waves from high energy electromagnetic waves and for focusing said separated high energy electromagnetic waves comprising a container having closely spaced walls of selected curvature, said container enclosing a quantity of ionizable gas, said walls and ionizable gas being transparent to low energy electromagnetic waves, said ionizable gas becoming dissociated into its ions when subjected to high energy electromagnetic waves and acting as a reflector, said selected curvature of said closely spaced walls determining the shape of said reflector and the place at which said high energy waves may be focused, said closely spaced walls having larger extent than a wavelength in a direction perpendicular to the direction of propagation of said electromagnetic waves to form said reflector and to reduce the concentration of electromagnetic energy.

10. A device for separating low energy electromagnetic waves from high energy electromagnetic waves and for focusing said separated high energy electromagnetic waves comprising a container having closely spaced walls of selected curvature, said container enclosing a quantity of ionizable gas, said walls and ionizable gas being transparent to low energy electromagnetic waves, said ionizable gas becoming dissociated into its ions when subjected to high energy electromagnetic waves and acting as a reflector, said selected curvature of said closely spaced walls determining the shape of said reflector and the plane in which said high energy waves may be focused, and the extension of said closely spaced walls to dimensions greater than a wavelength of said electromagnetic waves in a direction perpendicular to the direction of propagation of said electromagnetic waves serving to reduce the concentration of electromagnetic energy per unit volume of said reflector.

11. A controller for electromagnetic waves comprising means including a closed container for confining a quantity of ionizable gas, said closed container having walls of desired shape selected to restrain said ionizable gas within a volume of space having a particular shape, said ionizable gas transmitting low energy electromagnetic signals, said ionizable gas responding to high energy electromagnetic signals to become ionized, and said gas on being ionized forming a reflecting zone within said walls of desired shape to reflect said high energy electromagnetic signals to form focused images at least along one line in a plane perpendicular to the direction of propagation of said electromagnetic waves.

12. A reflector substantially as claimed in claim 1 in which said closed container comprises a plurality of long tubular sections having independent closures of gas.

13. A reflector substantially as claimed in claim 2 in which said closed container comprises a plurality of long tubular sections having independent closures of gas.

14. A reflector substantially as claimed in claim 3 in which said closed container comprises a plurality of long tubular sections having independent closures of gas.
